UNITED STATES PATENT OFFICE.

LEVI S. GARDNER, OF DETROIT, MICHIGAN.

CARBURETER.

1,316,706.

Specification of Letters Patent. Patented Sept. 23, 1919.

Application filed June 24, 1916. Serial No. 105,559.

To all whom it may concern:

Be it known that I, LEVI S. GARDNER, a citizen of the United States, residing at Detroit, county of Wayne, State of Michigan, have invented a certain new and useful Improvement in Carbureters, and declare the following to be a full, clear, and exact description of the same, such as will enable others skilled in the art to which it pertains to make and use the same, reference being had to the accompanying drawings, which form a part of this specification.

My invention has for its object to produce a simple and novel carbureter which shall be light and inexpensive and, without the employment of moving parts will operate effectively automatically to proportion the air and fuel to secure the greatest efficiency at all speeds of the engine.

20 A further object of my invention is to provide means for reducing the pressure on the supply of fuel as the speed of the engine increases, in order to prevent the fuel from being drawn out in solid streams at high speeds.

In attaining the last aforesaid object I cause a partial vacuum to be created in the fuel reservoir of a carbureter above the fuel therein and, since such partial vacuum assists in producing the required flow of fuel from an outside source into the carbureter reservoir, my invention may be said to have for one of its objects to produce a simple and novel means for drawing the fuel into the reservoir of a carbureter.

I have found that the best results in a carbureter for low engine speeds are obtained by means other than that which, on the other hand, produces the best results at higher speeds and therefore, regarded in one of its aspects, my invention may be said to have for its object, to produce a simple double carbureter having no moving parts and yet having two carbureting devices adapted to come into operation successively as the speed of the engine increases in starting.

50 A further object of my invention is to produce a simple and novel means for diluting the carbureted mixture manually.

The various features of novelty whereby my invention is characterized will hereinafter be pointed out with particularity in the claims; but, for a full understanding of my invention and of its objects and advantages, reference may be had to the following de-

tailed description taken in connection with the accompanying drawings, wherein:

Figure 1 is a central axial section through a carbureter arranged in accordance with 60 a preferred form of my invention;

Fig. 2 is a view partly in plan and partly in section of the carbureter illustrated in Fig. 1;

Fig. 3 is a section taken approximately 65 in line 3—3 of Fig. 1;

Fig. 4 is a transverse central section taken at right angles to the plane of Fig. 1; and

Fig. 5 is a view similar to Fig. 4 illustrating a slight modification.

The present carbureter operates on a principle similar to that of my prior Patent 1,183,864, granted May 23, 1916, and in one aspect, may be regarded as constituting an improvement on the construction illustrated 70 in the aforesaid patent. In the present carbureter, as in the one in my prior patent, the main supply of fuel is delivered in a stream of air passing across a body of the fuel; fuel at low speeds being delivered without 80 passing through the main delivery tube. The details are, however, different and these differences introduce new functions and results.

Referring first to Figs. 1 to 4 of the drawings, 1 represents a tubular member in the form of a Venturi tube forming the body of the carbureter. The axis of the member 1 is horizontal and, projecting downwardly from the middle of the member 1 is a post, 90 2. Seated against the lower end of the post is the bottom of a bowl, 3, of usual construction whose upper end is closed by a portion of the casting of which the body member is made. The bowl may conveniently be held 95 in place by means of a short headed screw, 4, which enters the lower end of the post and serves as a plug for a well or passage, 5, of considerable capacity formed in the post. Fuel flows from the bowl or reservoir, where 100 it is kept at a constant level, into the well or passage, 5, through a suitable port, 6. In the arrangement shown, the port 6 has two inlet ends, 7 and 8, the latter of which is controlled by a thermostatic valve, 9, but 105 this feature forms no part of the present invention and forms the subject of a separate application dated June 24, 1914, and bearing the serial number 105,560.

In one end of the body member of the 110 carbureter is a shut-off valve, 10, while in the other end is a throttle valve, 11. A pas-

sage, 12, extends through the wall of the body member from a point beyond the throttle to a point within the main air passage, preferably in advance of the contracted neck of the Venturi tube so that when the throttle is closed air will be drawn through this passage which therefore serves as a bypass around the throttle valve. The inlet end, 13, of the passage 12 is preferably made larger than the remainder of the passage. Leading downwardly from the enlarged end, 13, of the passage is a passage, 14, which opens at its lower end into the lower end of the well or chamber 5 in the post 2. With this arrangement, when the engine is running slowly, the throttle valve being closed, air is drawn through the passage 12 and, by creating a suction in the passage 14, draws up fuel and delivers it to the engine. When the throttle valve is opened more or less the difference in pressure between the two ends of the passage 12 decreases and the supply of fuel drawn through the same also decreases. From the upper portion of the well or chamber 5 extends a passage, 15, which communicates with atmosphere, preferably through a restricted port, 16, as shown in Fig. 4, or, if desired, with the main air passage in the carbureter, through a branch port or passage, 17, as shown in Fig. 2, similar to the part 13 of the passage 12. Either or both of the ports or passages 16 and 17 may be employed and if only the latter, then where the air supplied to the carbureter is heated, only warm air will be drawn through the passage 15. From the well or chamber 5 extends a tube, 18, having its upper end bent so as to bring the mouth thereof at the axis of the Venturi tube and approximately in the plane of the narrow neck. When the throttle valve is open, air flows downwardly through the passage 15, picks up fuel from the well or chamber 5, and carries it up through the delivery tube, 18. By reason of the presence of the auxiliary fuel feeding passage, 14, leading from the bottom of the well or chamber 5, it will often happen that when the main delivery devices are brought into play it is after the fuel level in the well or chamber 5 has fallen considerably below the normal fuel level in the reservoir as indicated by the dotted line X—X and therefore, in order to make the main fuel feeding devices operative, I extend the tube 18 down into the chamber or well a considerable distance below the liquid level in the reservoir; thus bringing it in the vicinity of a new normal fluid level resulting from the withdrawal of the fuel through the passage 14 and permitting the air entering the passage 15 to flow over the top of the liquid fuel and up into the tube 18.

In Fig. 5 the construction is just like that heretofore described except that instead of the passage 14 opening into the chamber or

well 5 so as to draw fuel therefrom, a small tube extending from the enlarged end, 13, of the passage 12 down into the reservoir, and opening into the reservoir at a considerable distance below the normal fluid level 70 therein, is employed. With this construction just the same results as with the other are secured except that the flow through the tube 20 is not regulated by the thermostatic valve where the latter is used. Furthermore, with 75 this construction, the only fuel that is drawn out of the chamber or well 5 is that which flows up through the delivery tube 18 and therefore this tube may be made to terminate above the plane of the normal level in the 80 reservoir, as is also a portion of the lower end of the passage 15, so that there is only one normal liquid level which need be considered, instead of the two normal liquid levels of the other form. 85

Reference being again had to Fig. 1, it will be seen that the top of the fuel reservoir which is tightly closed by the body member of the carbureter, communicates with the air passage in the carbureter through a small 90 port, 21, which is thus placed at a point where the pressure is below that of atmosphere when the engine is running. The result is that a partial vacuum is maintained above the fuel in the reservoir, this vacuum increasing as the speed of the engine increases, thus preventing the fuel from being drawn out in a solid stream and at the same time permitting the feed of the fuel into the reservoir to be caused in part, at least, by reason 100 of the difference in pressure at the surface of the fuel in the carbureter reservoir and at the surface of the fuel in the storage reservoir. It will be seen that by varying the point in the air passage of the carbureter 105 at which the port 21 is situated, a variation in the vacuum effect will be produced, and the closer the port is to the engine end of the carbureter, the greater will be the vacuum.

Another feature of my invention has to do 110 with diluting the carbureted mixture before it leaves the carbureter. To this end I have placed on the body of the carbureter, just before the throttle valve is reached, a tubular projection, 30, the space within which 115 communicates with the main air passage in the carbureter. A hole, 31, is drilled through the sleeve. In the outer end of the sleeve is seated a rotatable plug, 32, serving as a stopper. In the inner end of the plug is cut 120 a wide slot, 33, which, in one position of the plug, registers with the opening 31 and permits air from the outside to be drawn into the carbureter and mingle with the carbureted mixture while, when the plug is 125 turned at right angles to the aforesaid position, the portions forming the sides of the slot serve as valves to close the opening 31. The plug may conveniently be held in place 130 and be limited to movements from a fully

closed to a fully open position by cutting in the member 30 a slot, 34, lying in a plane at right angles to the axis of the plug, and inserting a pin, 35, through this slot into the 5 plug. The pin prevents the plug from being lifted out and the slot limits the extent to which the plug may be turned.

While I have illustrated and described only a single preferred form of my invention, with a slight modification, I do not desire to be limited to the exact structural details thus illustrated and described; but intend to cover all forms and arrangements which come within the terms employed in 10 the definitions of my invention constituting the appended claims.

I claim:

1. A carbureter having a Venturi tube arranged with its axis horizontal, a post extending downwardly from the Venturi tube and hollowed out in the lower end so as to 20 form a well, a constant level fuel reservoir surrounding said post and communicating with the well therein through a restricted 25 passage, an open-ended imperforate tube of larger diameter than said restricted passage

extending from the well into the Venturi tube and terminating at the contracted neck of the latter, and an air passage extending from the exterior of the carbureter into said 30 well.

2. A carbureter having a Venturi tube arranged with its axis horizontal, a post extending downwardly from the Venturi tube and hollowed out in the lower end so as to 35 form a well, a constant level fuel reservoir surrounding said post and communicating with the well therein through a restricted passage, an open-ended imperforate tube of 40 larger diameter than said restricted passage extending from the well into the Venturi tube and terminating at the contracted neck of the latter, an air passage extending from the exterior of the carbureter into said well, and a restricted passage leading from the 45 well into the Venturi tube at a point remote from the upper end of said open-ended tube.

In testimony whereof I sign this specification.

LEVI S. GARDNER.
